UNITED STATES PATENT OFFICE.

STEPHEN JOSEPH DERBES, OF NEW ORLEANS, LOUISIANA.

ELECTRIC SIGNAL FOR WEIGHING-SCALES.

No. 833,447.

Specification of Letters Patent.

Patented Oct. 16, 1906.

Application filed November 28, 1905. Serial No. 289,492.

To all whom it may concern:

Be it known that I, STEPHEN JOSEPH DERBES, a citizen of the United States, and a resident of New Orleans, in the parish of Orleans and State of Louisiana, have invented a new and Improved Electric Signal for Weighing-Scales, of which the following is a full, clear, and exact description.

This invention relates to signals; and it consists, substantially, in the details of construction and combinations of parts herein-after more particularly described, and pointed out in the claims.

The invention has reference more especially to electric alarm-signals for association with some part of a weighing scale or machine to be operated by the scale-beam for indicating to a salesman or other attendant of a store or other establishment that goods being weighed on the scale are approaching the weight at which a balance will be established therebetween and the poise or poises on the scale-beam.

One of the principal objects of the invention is to provide an electric alarm-signal for the purpose named which is simple in construction and comparatively inexpensive to manufacture, besides being effective and reliable in operation and possessing the capacity for long and repeated service.

The above and additional objects are attained by means substantially such as are illustrated in the accompanying drawings, in which—

Figure 1 is a side view of the upper portion of a weighing-scale having my improvements applied thereto. Fig. 2 is an enlarged transverse sectional view on the line 2-2 of Fig. 1 and showing the battery, bell, and electric circuit employed. Fig. 3 is a top plan view, and Fig. 4 is an end view.

Before proceeding with a more detailed description it may be stated that in the form of my improvements herein shown special means are employed for mounting the main elements thereof upon some part of a weighing-scale—say, for instance, the shelf which supports the scale-beam—an alarm-bell being also employed, together with further special means disposed within the vicinity of the scale-beam and operated thereby to cause

the bell to ring in the manner to be explained.

The device further comprises an electric battery and an electric circuit in which the alarm-bell is included, the said special means second above referred to being also included in the circuit and constituting practically a switch for opening and closing the same.

Reference being had to the drawings by the designating characters thereon, 1 represents the shelf or upper part of an ordinary weighing-scale, centrally of which is a post 2, by which the arm 3 of the scale-beam 4 is pivotally supported at 5 in the usual manner, said shelf being formed at one end thereof with a guard 6, in which works the curved end 7 of the scale-beam, to which is suspended at 8 the balancing-poise 9 and on which is carried the usual slidable indicating-poise 10.

My improved electric alarm-signal comprises a strip 11 of wood or other insulating material laid across the upper surface of the said shelf 1 of the weighing-scale, one end of the said strip being flush with one side of the shelf and the other end thereof projecting slightly beyond the other side of the shelf—as indicated at 12, for instance. Applied to the strip 11 at the last-mentioned end thereof is an angle-plate 13, the horizontal member 14 of which rests in contact with the upper side of the strip and is secured to the latter in any suitable way, as by means of screws 15. The vertical member 16 of the said angle-plate 13 is secured to the projecting end 12 of the strip 11, also by means of screws 17, the said member being provided with a holder 18 for a vertically-disposed electric contact member 19, having the upper end thereof bent into the form of a hook 20, said contact member being adjustably held in said holder by means of a set-screw 21, it being mentioned that the holder is secured to the said vertical member 16 of the angle-plate 13 in any suitable way, as by means of a binding-screw 22, extending through the member 16 from the inner side thereof, as shown in Fig. 2.

The shelf 1 is provided at the side thereof, adjacent to the member 16 of the angle-plate

13, with a plate or disk 23, of insulating material, and against which bear the ends of set-screws 23^a, working through suitable openings therefor in the member 16 and employed 5 for the purpose of adjustably attaching the angle-plate 13 and its auxiliaries to the said shelf 1.

Applied to the opposite end of the said strip 11 is another angle-plate 24, the horizontal member 25 of which rests upon the strip 11 and is secured thereto by means of screws 26 and the vertical member 27 of which fits close to the adjacent side of the shelf 1, being secured to the end of the strip 15 11 by means of screws 28 or in any other suitable way. This vertical member 27 of the angle-plate 24 is also provided with a holder 29 for the vertical portion 30 of another electric contact member 30^a, comprising also 20 an integral horizontal spring or elastic portion 31, extending across the shelf 1 at a suitable height above the angle-plate referred to, with the free end portion thereof located within the bill of the hook 20 and normally 25 held or maintained out of electric contact with said hook by the weight of the arm 3 of the scale-beam, which rests thereon, as indicated in Fig. 2. The said vertical portion 30 of the second-mentioned contact member is adjustably held within its holder by means of a set-screw 32, this holder being secured to the member 27 of the angle-plate 24 by means of a screw 33. A suitable electric battery 34 is employed, the same being located in any desired position with reference to the shelf 1 of the weighing-scale, and connecting with one pole thereof is one end of an electric conductor 35, the other end of which is secured to the holder 29 for the second above-mentioned 35 contact member. Connecting with the other pole of said battery is one end of a short conductor 36, the other end of which is in electrical connection at 37 which a binding-screw on an alarm-bell 38, while connecting with another binding-screw 39 on the alarm-bell is 40 one end of another electric conductor 40, the other end of which is held in electric contact with the holder 18 for the contact member 19 by means of the said mentioned binding-screw 22. In this way a normally open electric circuit is derived; but as soon as the arm 3 of the scale-beam is caused to move upwardly the slightest extent the inherent resiliency of the horizontal portion 31 of the contact member 30^a immediately carries the free end of said portion into contact with the hook 20 of the contact member 19, thereby closing the circuit and causing the alarm-bell to ring in an obvious manner. 45 From the foregoing it will be seen that when the weighing-scale is not in use the weight of the arm 3 will maintain the horizontal portion 31 of the contact member 30^a

out of electrical contact with the hook 20 of the contact member 19, and this relation will 65 be also maintained until the scale-beam is caused first to rise by the placing of goods on the scales to be weighed, thus giving notice to the operator or attendant weighing the goods that the weight of the goods is approaching 70 that at which a balance will be established between the same and the poise or poises on the scale-beam.

Having thus described my invention, I claim as new and desire to secure by Letters 75 Patent—

1. In a weighing-scale provided with a shelf, the combination with the scale-beam, of an insulating-strip applied to the shelf, rods adjustably connected with the strip, one 80 of said rods terminating in a hook, and the other having a horizontal resilient portion extending beneath the scale-beam, and projecting within the hook, and an electric circuit including a signal having its terminals in 85 the rods.

2. In a weighing-scale provided with a shelf, the combination with the scale-beam, of an insulating-strip applied to the shelf, angle-plates having horizontal members secured to the strip, and vertical members projecting downwardly therefrom, one of said vertical members being insulated from the shelf, an electric circuit including an alarm having its terminals connected with the 95 angle-plates, and means whereby the movement of the scale-beam may act upon the terminals to close the circuit.

3. In a weighing-scale, provided with a shelf, the combination with the scale-beam, 100 of a strip of insulating material applied to the shelf and projecting beyond the side thereof at one of its ends, angle-plates secured to said strip at its ends, having vertical members disposed on the sides of the shelf, a strip 105 of insulating material between one of said vertical members and the shelf, an electric battery, an electric circuit, including an alarm-bell therein, and having terminals supported by the angle-plates, one of which comprises 110 a hook, and the other a horizontal resilient portion, normally held under tension by weight of the scale-beam thereon, the free end of which portion projects within said hook. 115

4. In a weighing-scale, provided with a shelf, the combination with the scale-beam, of a strip of insulating material applied to the shelf and projecting beyond the side thereof at one of its ends, angle-plates secured to 120 said strip at its ends, having vertical members disposed on the sides of the shelf, an electric battery, an electric circuit, including an alarm-bell therein, and having terminals supported by the angle-plates, one of which 125 comprises a hook, and the other a horizontal

resilient portion, normally held under tension by weight of the scale-beam theréon, the free end of which portion projects within said hook, the vertical member of one of the angle-plates being provided with fastening-screws therefor to said shelf, and the latter having an insulating-plate, against which the ends of said screws bear.

In testimony whereof I have signed my name to this specification in the presence of 10 two subscribing witnesses.

STEPHEN JOSEPH DERBES.
